UNITED STATES PATENT OFFICE.

THOMAS C. LACKLAND, OF NORFOLK, VIRGINIA.

FILTER.

1,261,558.

Specification of Letters Patent. Patented Apr. 2, 1918.

Application filed August 31, 1915. Serial No. 48,289.

To all whom it may concern:

Be it known that I, THOMAS C. LACKLAND, a citizen of the United States, residing at Norfolk, in the county of Norfolk and State 5 of Virginia, have invented new and useful Improvements in Filters, of which the following is a specification.

My invention relates to filters, and more particularly to a portable water filter which 10 is adapted to be attached to the ordinary water cock or faucet.

In carrying out my invention it is my purpose to provide a filter which is adapted to accommodate a filtering material such as 15 paper, which may be frequently changed without incurring great expense. In order to permit the ready application and removal of the filtering paper I have constructed a casing or shell which comprises two hemi- 20 spherical sections, one of which rigidly supports the filtering paper therein, the confronting edges of the sections being detachably connected so as to facilitate the separation of the sections and permit the ready 25 substitution of a new filtering material.

Another purpose of my invention is to provide a filter so constructed as to permit the same to be rapidly applied to and removed from a faucet.

With the above and other objects in view, 30 the invention consists in the features of construction, combination and arrangement of parts hereinafter described and claimed, reference being had to the accompanying drawings, in which:

Figure 1 is a side elevation of my device showing it applied to a faucet;

Fig. 2 is a vertical section;

Fig. 3 is a horizontal section;

Fig. 4 is an enlarged collective view of 40 the filter, showing the sections in perspective;

Fig. 5 is a top plan view of the perforated plate supporting member for the filtering 45 paper; and

Fig. 6 is a horizontal sectional view of the metallic ring.

Fig. 7 is a fragmentary view of the inner 50 wall of the upper semi-spherical member showing the inclined slots formed therein.

Referring to the drawings in detail, the body of the filter consists of two hemispherical members, 1 designating the upper member and 2 the lower member. The upper 55 member is provided with a centrally arranged nipple 3 which is split longitudi-

nally, as at 4. Mounted upon the nipple and capable of sliding movement thereon is a clamping nut 5. To secure a rigid water-tight connection between the nipple 60 and the nozzle of the faucet 6 I have provided the inside of the nipple with a short flexible pipe 7, such as rubber or the like, of a corresponding length and which is adapted to normally lie contiguous to the 65 inner wall of the nipple, whereby upon upward movement of the clamping nut 5, owing to the longitudinal splits, the nipple will be compressed, thereby causing the pipe 70 to snugly engage the nozzle of the faucet. Mounted upon the inner wall of the upper member adjacent the lower edge thereof are an annular series of ribs 8 which have the confronting ends thereof spaced to form entrance slots 9. The upper edges of the ribs 75 are inclined, as at 10, from one end to the opposite end. Arranged above the annular series of ribs 8 is an annular rib 11 which is provided with thickened portions 12 adjacent each of the ribs 8, said portions having the lower edges thereof inclined in the opposite direction to the adjacent edge 10 of the ribs 8 and coöperating with the same to form inclined slots 13.

The lower end of the lower member 2 is 85 provided with an outlet 14 arranged centrally thereon and in axial alinement with the nipple 3 on the upper member. The outer wall of the upper member is provided with a series of laterally extending lugs 15 90 adjacent the upper edge thereof, said lugs being adapted to work within the inclined slots 13 when connected to the upper member. In the present instance I have shown four lugs upon the lower member which correspond to the number of slots formed in the upper member, and I wish it to be understood that any number of slots or lugs may 95 be used. As will be hereinafter described, the lower member is provided with operating handles 16 adapted to be used when moving the lugs within the slots 13 to lock the hemispherical members together. Formed upon the inner wall of the casing are a series of vertically extending ribs 17, 100 which have their upper ends thickened to form a support, said ends terminating at a point adjacent the upper edge of the hemispherical member. These vertically extending ribs are arranged at diametrically opposite points and rigidly support a perforated 105 disk or plate 18, the enlarged portions of

the ribs engage the marginal edges of the disk. Mounted upon the disk 18 and engaging the marginal edges thereof is a metallic annular ring 19 which is L-shaped 5 in cross section and which has the horizontal flange thereof engaging the inner wall of the lower member, whereby a substantially U-shaped channel is formed to receive a rubber washer 20 which is rectangular in 10 cross section, in this construction it will be seen that a perfectly water-tight connection is formed between the upper and lower members when they are in their locked position, the rubber washer serving to prevent escape 15 of the liquid between the confronting edges of the members. Arranged upon the top surface of the disk 18 is the filtering material, it being, in this instance, a sheet of porous paper 21, of a shape corresponding to 20 that of the disk, the marginal edges of the sheet lying beneath the ring 19 so that the same will be held securely upon the disk against the force of the water.

It will be seen from the foregoing construction that when it is desired to assemble the parts as shown in Fig. 1, the disk 18 is placed upon the vertically extending ribs 17. The filtering material is then arranged upon the disk so as to lie contiguous 25 thereto. The ring 19 and the washer 20 are then applied to the marginal edges of the paper, as has been previously described, whereupon the hemispherical member is moved in a position so as to cause the lugs 15 to register with the entrance slots 9. Upon moving the member upwardly and imparting partial rotary motion thereto by the operating handles 16 the lugs will be moved circumferentially into the inclined slots 13, 30 whereby the confronting edges of the respective members will be brought into tight engagement with each other and the members securely locked. It will be noted that the annular rib 11 is of such a width as to form 35 an abutment for the washer 20 when the members are in their locked position whereby a water tight joint will be formed between the members and any escaping of the liquid through the confronting edges of the 40 members will be prevented.

From the foregoing construction it will be seen that the filtering paper may be readily applied and removed from the casing and that the lower member may be quickly attached to the upper member without the use 45 of nuts, bolts or the like. When it is desired to replace the filtering paper or clean the interior of the casing, by imparting a

reverse rotary motion to the member the lugs will be withdrawn from the slots, 60 whereupon the members may be separated.

When it is desired to apply my improved form of filter to a faucet of the common construction the nozzle of the faucet is inserted into the rubber pipe 7, and the clamping 65 nut is then moved upwardly, whereby the split sections of the nipple will be moved toward each other, thus causing the pipe to tightly engage the nozzle and securely hold 70 the filter upon the faucet.

In use, the water flowing in at the nipple strikes the paper sheet of filtering material, whereby the water is distributed over the entire surface of the sheet. The water then percolates through the paper, filtering the 75 same of sand, dirt or the like and finally through the perforated disk, the disk serving to retard the force of the water so that the filtering material will thoroughly strain 80 the water. This disk further serves to form a rigid support for the paper and prevent the latter from being broken and disintegrated by the force of the water thereupon.

Having thus described my invention, I claim:

In a device of the character described comprising a pair of substantially semi-spherical members, means for coupling said members together comprising lugs extending outwardly from the periphery of one of 90 said members adjacent its open end, the inner periphery of the other member being provided with vertical slots extending from its open end and communicating with upwardly inclined slots, the highest points of 95 said inclined slots also communicating with said vertical slots, an inwardly extending annular flange on said second named member, an L-shaped ring supported within said first named member and contacting with its 100 inner periphery, and a resilient ring rectangular in cross section disposed upon the horizontal portion of said L-shaped ring and engaging the inner periphery of said first named member and extending beyond the 105 open end thereof and engaging said flange said lugs being engageable in said inclined slots by upward and partial rotary movement of said first named member.

In testimony whereof I affix my signature 110 in presence of two witnesses.

THOMAS C. LACKLAND.
